UNITED STATES PATENT OFFICE.

RAPHAEL JACOBUCCI, OF FALL RIVER, MASSACHUSETTS, ASSIGNOR OF ONE-HALF TO
JAMES A. GOURKE, JR., OF FALL RIVER, MASSACHUSETTS.

MULTICOLOR-PRINTING MACHINE.

1,240,159.

Specification of Letters Patent. Patented Sept. 11, 1917.

Application filed October 14, 1916. Serial No. 125,717.

To all whom it may concern:

Be it known that I, RAPHAEL JACOBUCCI, a citizen of the United States, residing at Fall River, in the county of Bristol and State of Massachusetts, have invented certain new and useful Improvements in Multicolor-Printing Machines; and I do hereby declare the following to be a full, clear, and exact description of the invention, such as 10 will enable others skilled in the art to which it appertains to make and use the same.

This invention relates to printing, and more especially to multi-color machines; and the object of the same is to improve certain details as set forth below.

An important feature of this invention lies in the use of the ordinary intermittently rotating disk with or without a fountain, for each color of ink, and the use of a number of 20 these disks at intervals in a rotary table along with sets of rollers and means for causing the rollers automatically to engage their proper disks only.

Another feature of the invention consists 25 in mounting a set of bed plates at intervals in said table, and providing means for permitting the rollers of one color only to drop onto each plate as the latter passes beneath them.

30 Another feature of the invention is the means for diverting each form from its circular path and directing it along a straight path at a time when it is passing beneath the cylinder.

35 Other details will appear in the following specification, reference being had to the accompanying drawings wherein:

Figure 1 is a plan view of the press with parts partly broken away to show details of 40 construction and with parts in section.

Fig. 2 is a vertical transverse section on line 2—2 of Fig. 1.

Fig. 3 is a fragmentary detail showing the ink plate and fountain actuating mechanism.

45 Rising from a suitable support such as sills 1 are standards 2 carrying an annular base 3 which in turn carries a number of anti-friction devices or wheels 4. At the center of the standards rises a pillar 5 on which is rotatably mounted a sleeve 6 carrying a beveled gear 7, and meshing therewith is another gear 8 at the inner end of a power shaft 9 mounted in suitable bearings 10 and having fast and loose pulleys at

its outer end so that it may be rotated from 55 any suitable source. From the hub 11 of the driven gear 7 radiate spokes 12 carrying at their outer ends a rotary table 13 shown in the drawings as of skeleton formation and made up of two rings whereof the outermost 60 travels on the wheels 4, although this is a matter of detail and there might be two sets of wheels or the rotary table might be solid. Said table carries the bed plates for the 65 chases and the inking plates or disks for inks of several colors, and in the accompanying drawings I have shown three of each so that this machine is adapted to print in three colors. However, I do not wish to be limited in this respect as there might be a greater 70 number of colors, and in a large machine I would probably make provision for a greater number and then use only such as desired.

The inking mechanism.—Each inking plate or disk 20 is rotatably mounted on a 75 pin 21 and carries on its under side teeth 22 as usual, and adjacent each disk a fountain 23 is by preference employed. The usual mechanism 24 may be used for intermittently rotating the disk and causing the feed 80 of the fountain, and this mechanism is actuated by a lever 25 tripped by a cam 26 or a series of cams located preferably in advance of the cylinder as seen. For each disk the table carries a track made up of inner and 85 outer rails. In the drawings I have shown red, yellow and blue disks for illustrative purposes only, and I have shown three tracks differing in gage from each other and which I have purposely shaded to correspond in 90 color with their respective disks. I am now describing the red disk 20, whose track is of the widest gage and whose rails are numbered 27 and 28. It will be observed that these rails are depressed or entirely removed 95 at points 29 opposite the disk 20 and a little in advance and a little in rear of it.

At the upper end of the pillar 5 is a head 30 on which is mounted a spider 31 carrying in the present case three arms 32 each having 100 at its outer end an upright plate 33 provided with a series of slots 34; and rising rigidly from the base 3 is a similar plate 35 having an equal number of upright slots 36. In said slots rest the trunnions 37 of a set of 105 rollers 38, and each roller has on its trunnions wheels 39 spaced according to the gage of the rails 27 and 28. In the present

instance the red rollers and their track are of wide gage, the yellow rollers and their track intermediate gage, and the blue rollers and their track narrow gage. However, 5 this arrangement is a matter of choice, and of course it would have to be amplified if there were more than three set of rollers. In any case the tracks are depressed or omitted at 29 opposite the disk as described 10 above, and therefore in the rotation of the table 13 whenever any disk approaches its corresponding set of rollers the depressed track permits their wheels 39 and their bodies 38 to drop onto that disk from which 15 they receive ink in the usual manner. In the arrangement shown, three disks precede three type beds numbered respectively 40, 41 and 42. Continuing the description of the red, the tracks 27 and 28 are depressed or 20 omitted at 49 opposite the bed 40 whose type are to be inked in red, and a little in advance and a little in rear of the same; and therefore as the chase containing these type approaches the set of red rollers, they descend 25 and the inking is accomplished. As soon as this chase has passed, the rollers rise onto the tracks beyond the depressions 49 so that they spread no ink onto the type in the chases on the yellow bed 41 and the 30 blue bed 42, both of which do get their ink, however, from the proper set of rollers.

The paper feed.—The head 30 carries a bearing 50 opposite the spider 31, and another bearing 51 is carried by the base, preferably on an extra standard 2'. In these bearings are mounted trunnions 52 of a cylinder 53, whose inner end carries a gear 54 meshing with a gear ring 55 fixed to and rising from the spokes 12 and standing just 40 inside the innermost rails of the several tracks, and moving just inside the several plates 33. By these means the revolution of the table is communicated to the cylinder, and the latter is caused to revolve reliably 45 in unison therewith, no matter at what speed the machine is run. I have shown only in outline the feed board for the paper, the gripper fingers on the cylinder, the crank lever 56 at the inner end of the same, and its trip 57 inside the gear ring 55—none of 50 which mechanism I claim to have invented, but all of which is necessary in the successful operation of this machine as described below.

55 *The printing mechanism.*—In the present instance one-half of the cylinder is its working surface and the other half is cut away, and the bed plates are so disposed and proportioned that they co-act with the working surface while the spaces between them register with the cut-away portion of the cylinder. So also the disks come under the working surface of the rotating cylinder, but as they are lower their inked surfaces are not 60 in contact with it; and the spaces between 65

the disks also register with the cut-away portion of the cylinder. In other words, the latter makes six revolutions to one complete rotation of the table 13. If printing is to be done in three colors, the trip 57 is so located as to engage the lever 56 and open the gripper fingers to release the paper, only after the same has made three revolutions with the cylinder, but the details of the paper feed need not be amplified. In order 70 now to cause each bed plate to move along a strictly straight path as it passes beneath the cylinder, and while the printing is actually being done, I mount the plate loosely on the table in such manner that it may have a 75 slight movement either way from its position truly radial to such table, and provide fixed guides extending beneath the cylinder and against which the outer and inner ends of the plate slidably move at the proper 80 time. While I do not wish to be limited in this respect, the loose mounting referred to is shown as accomplished by pins 60 and 61 rising from the table if the same is solid or 85 spokes therein if the same is open, and grooves or slots 62 and 63 in the lower face of each plate loosely engaging said pins, play in this arrangement providing for relative turning of the plate. This will cause 90 the plate to progress along its circular path as the table rotates, while yet permitting the plate to swing to and fro with respect to a true radial position. Beneath the cylinder 95 53 and just outside the inner track 27 is located a straight guide 64 having a finger 100 65 at what will be its inlet end, and similarly beneath the cylinder and just inside the outer track 28 is located a straight guide 66 having a longer and yielding finger 67 at its inlet end. These guides are rigidly mounted 105 100 in any suitable manner, preferably by arms 68 and 69 leading respectively to the bearings 50 and 51.

Operation.—Let us assume now that the machine is to print three forms in red, yellow and blue respectively. The chases containing the forms are mounted on the bed plates 40, 41 and 42; and the proper colors applied to the disks either directly or by means of the fountains 23 if they exist. 110 Paper is then fed to the cylinder either by hand or mechanically—this detail forming no part of the invention—and when power is applied to the shaft 9 the intermeshing beveled gears cause the rotation of the table 115 13 and the ring 55 and gear 54 cause the simultaneous revolution of the cylinder at the relative speed described above. When now the form (for red ink) in the chase upon the plate 40 passes beneath the set of rollers carrying red ink, the depressions 29 in the tracks permit the trunnions of said rollers to descend in the slots 34 and 36 in the plates 120 33 and 35 and the inking surface of the rollers contact with the surface of the type. 125 130

- As soon as the plate has passed this set of rollers, however, the tracks rise again and the rollers are lifted and held elevated while subsequent forms come under them and are 5 of course not inked. The same action takes place with the other forms and the rollers bearing ink of other colors. Also as each disk 20 comes under the set of rollers bearing ink of corresponding color, the depressions 10 29 in the tracks permit those rollers to descend and become inked, whereas at other times the rollers are held elevated excepting when they are inking the form as just described, and therefore inks of different colors 15 20 are not mixed. When now the first of the three forms approaches the cylinder, the inner and outer ends of its plate pass between the fingers 65 and 67 respectively, and as the plate can move slightly by reason of the pins 25 and slots described, these fingers direct it toward the straight guides 64 and 66 between which its ends are received just before it passes under the cylinder—all as perhaps best seen in Fig. 1. The position of 30 35 the paper on the cylinder is of course such that it is stretched across its working surface and held by the usual gripper fingers or tapes in a well-known manner, and while the form is passing under the working surface of the cylinder the latter is making half a revolution and the impression in the proper color is applied to the paper. The plate with its form now moves out from between the rear ends of the fixed guides and 40 45 50 55 60 65 70 75 80 85 90 95 100 105 110 115 120 125 130 135 140 145 150 155 160 165 170 175 180 185 190 4
roller onto one inking plate, then raising it, and then dropping it onto one form and raising it again.

6. In a multi-color press, the combination with a continuously rotating table, a plurality of bed plates loosely mounted at intervals thereon and carrying separate forms, the inking mechanism, and the cylinder; of parallel fixed guides extending beneath the cylinder and spaced to engage and direct a bed plate as it passes under the same, and yieldable means at the inlet ends of said guides for directing the approaching plates between them.

15 7. In a multi-color press, the combination with a rotary table, a plurality of bed plates

loosely mounted at intervals thereon and carrying separate forms, the inking mechanism, and the cylinder; of parallel fixed guides extending straight beneath the cylinder and spaced to engage and direct a bed plate as it passes straight under the same, and yielding fingers at the inlet ends of said guides between which an approaching plate is received and by which it is directed to the fingers.

20 In testimony whereof I affix my signature in presence of two witnesses.

25 RAPHAEL JACOBUCCI.

Witnesses:

N. L. COLLAMER,
JOHN L. FLETCHER.
